P. A. WAGNER.
REED FOR LOOMS.
APPLICATION FILED SEPT. 8, 1921.

1,413,950.

Patented Apr. 25, 1922.

Inventor:
Paul A. Wagner,
by his attorney,
Charles R. Searle.

UNITED STATES PATENT OFFICE.

PAUL A. WAGNER, OF JERSEY CITY, NEW JERSEY.

REED FOR LOOMS.

1,413,950.

Specification of Letters Patent. Patented Apr. 25, 1922.

Application filed September 8, 1921. Serial No. 499,133.

To all whom it may concern:

Be it known that I, PAUL A. WAGNER, a citizen of the United States, residing at Jersey City, in the county of Hudson and State of New Jersey, have invented a certain new and useful Improvement in Reeds for Looms, of which the following is a specification.

The object of the invention is to provide 10 a reed, easily and economically manufactured, in which the dents are accurately, uniformly and closely spaced. Another object is to provide compressible or yielding spacing means at the ends of the dents within 15 the bands, arranged to permit the spaces between the dents to be lessened in the process of manufacture, as required in producing the desired number of dents per inch.

A further important object is to provide 20 a reed structure in which a worn or defective dent may be removed and another substituted without destroying the reed.

The invention consists in certain novel 25 features of construction and arrangement by which the above objects are attained, to be hereinafter described and claimed.

The accompanying drawings form a part 30 of this specification and show an approved form of the invention.

Figure 1 is a face view of a metallic ribbon serving when folded as the spacing means.

Figure 2 is an edge view of the same.

Figure 3 is an edge view corresponding 35 to Figure 2, showing the ribbon partly folded.

Figure 4 is a horizontal section of the same.

Figure 5 is an edge view of a portion of 40 one convolution or fold, corresponding to Figure 3, and on a greatly exaggerated scale.

Figure 6 is a corresponding horizontal section.

Figure 7 is a face view of a portion of a 45 reed on a large scale, with certain portions broken away to show the parts beyond.

Figure 8 is a vertical section corresponding to the preceding figure.

Figure 9 is a horizontal section through 50 adjacent dents, showing in plan view the completely folded ribbon and the position of the dents relatively thereto, on the same scale as Figures 5 and 6.

Figure 10 is a face view on a small scale 55 showing the completed reed.

Similar reference numerals indicate the same parts in all the figures.

The spacing means for the improved reed is a ribbon of thin metal folded back and forth upon itself in sharp serpentine bends or convolutions, with the dents inserted on one face in the spaces between the partitions thus formed, and held separated by such partitions. One of such ribbons receives the upper ends of the dents and another receives the lower ends, within the bands.

Referring to the drawings, 1 is a narrow ribbon of thin metal having on one face 70 equally spaced wide transverse scores or grooves 2, and on the other face narrower grooves 3 midway between the grooves 2. The grooves serve as weakened lines for facilitating the bending. Each groove is 75 perforated as at 4 and the ribbon between the grooves is pricked or punctured as at 5 to produce groups of slight elevations or protuberances on one face of the ribbon. The folding of the ribbon into sharp ac 80 cordion bends is shown as initiated in Figures 3 and 4 and completed in Figure 9. The narrower grooves 3 permit a close fold by which the adjacent faces of the ribbon lie in close contact with each other to form 85 a series of partitions 6 separated each from the next adjacent by a space produced by the reverse fold along the wider groove 2.

Two separated ribbons thus formed receive the dents 7 in the spaces between the 90 partitions, with the extreme ends of the dents projecting slightly beyond the ribbons, as shown in Figures 7 and 8, and the side faces of the dent-ends are held out of direct contact with the adjacent inner faces 95 of the partitions 6 by the slight protuberances 5.

Thus assembled the dents are held in place by lateral pressure on the series with the dents equally spaced, and the spacing 100 may be slightly lessened by applying sufficient pressure to break down or upset the protuberances 5 and thus reduce the width of the spaces in which the dent-ends are received.

The bands 8 in which the ribbons and dent-ends are mounted each has a channel 9 receiving the inner projecting folds of the ribbon at the wider grooves 2, and has a flange 10 matching the projecting ends 110 of the dents, as in Figures 7 and 8. The end bars 11 are applied as usual and the

whole soldered by dipping or otherwise, the perforations 4 permitting the solder to flow to all the surfaces.

A thin strip 12, preferably of the same width as the band 8, may be applied to cover the outer edges of the dents and the outer ends of the partitions 6 of the ribbons, and soldered in place to afford a finish to this face of the reed.

10. To remove a dent, the solder is softened by heat and the strips 12 removed to permit access to the ends of the worn or defective dent which is then removed and a perfect dent substituted. The strips 12 are then replaced and the whole permitted to cool and harden the solder.

The grooves 2 and 3 may be omitted and a plain ribbon employed with or without the perforations 4 and protuberances 5, and 20 other modifications may be made in the forms and proportions of the parts without departing from the principle of the invention.

I claim:

25. 1. In a reed, a series of dents separated at their ends by partitions formed by folding a ribbon upon itself.

2. In a reed, a series of dents separated at their ends by partitions formed by folding a ribbon upon itself, and compressible means on said partitions between the latter and said dents.

3. In a reed, a series of dents separated at their ends by a series of partitions formed by folding a ribbon upon itself on predetermined transverse lines.

4. In a reed, a series of dents separated at their ends by a series of partitions formed by folding a ribbon upon itself in serpentine convolutions, such ribbon having weakened transverse lines determining such folds.

5. In a reed, a series of dents separated at their ends by a series of partitions formed by folding a ribbon upon itself in serpentine convolutions, such ribbon having perforations in the lines of such folds.

6. In a reed, a series of dents separated at their ends by a series of partitions formed by folding a ribbon upon itself in serpentine convolutions, such ribbon having transverse grooves for determining the lines of such folds.

55. 7. In a reed, a series of dents separated at their ends by a series of partitions formed by folding a ribbon upon itself in serpentine convolutions, such ribbon having transverse grooves located alternately on each face for determining the lines of such folds.

8. In a reed, a series of dents separated at

their ends by a series of partitions formed by folding a ribbon upon itself in serpentine convolutions, such ribbon having equally spaced transverse wide grooves on one face alternating with equally spaced narrow transverse grooves on the other face for determining the lines of such folds, said narrow grooves serving to produce said partitions, and said wide grooves serving to produce the spaces between said partitions in which said dents are received.

9. In a reed, a series of dents separated at their ends by a series of partitions formed by folding a ribbon upon itself in serpentine convolutions, such ribbon having equally spaced wide transverse grooves on one face alternating with equally spaced narrow transverse grooves on the other face for determining the lines of such folds, said narrow grooves serving to produce said partitions, and said wide grooves serving to produce the spaces between said partitions in which said dents are received, and compressible protuberances formed on such ribbon on the faces of said partitions adjacent to said dents.

85. 10. In a reed, a series of dents separated at their ends by a series of partitions formed by folding a ribbon upon itself in serpentine convolutions, such ribbon having equally spaced wide transverse grooves on one face alternating with equally spaced narrow transverse grooves on the other face for determining the lines of such folds, said narrow grooves serving to produce said partitions, and said wide grooves serving to produce the spaces between said partitions in which said dents are received, such grooves having perforations therein extending through said ribbon.

11. In a reed, a series of dents separated by a series of partitions near their ends, formed by folding a ribbon upon itself in serpentine convolutions, and bands each having a channel receiving the inner folds of its ribbon, and a flange covering the ends of said dents.

105. 12. In a reed, a series of dents separated by a series of partitions near their ends, formed by folding a ribbon upon itself in serpentine convolutions, bands each having a channel receiving the inner folds of its ribbon, a flange on said band covering the ends of said dents, and a strip on each of said bands covering the outer folds of such ribbon.

115. In testimony that I claim the invention above set forth I affix my signature.

PAUL A. WAGNER.
